UNITED STATES PATENT OFFICE.

PETER BAUKIN, OF BELOIT, WISCONSIN, ASSIGNOR TO C. MATTISON MACHINE WORKS,
OF BELOIT, WISCONSIN, A CORPORATION OF WISCONSIN.

RUBBING OR POLISHING MACHINE.

1,135,491.

Specification of Letters Patent.

Patented Apr. 13, 1915.

Application filed December 8, 1913, Serial No. 805,206. Renewed December 23, 1914. Serial No. 878,823.

To all whom it may concern:

Be it known that I, PETER BAUKIN, a citizen of the United States, residing at Beloit, in the county of Rock and State of Wisconsin, have invented certain new and useful Improvements in Rubbing or Polishing Machines, of which the following is a specification.

This invention relates to machines for rubbing or polishing cabinet work, as, for example, the smoothing and polishing of varnished surfaces of furniture.

In the process of "finishing" cabinet work, it is customary to rub the varnished surfaces after each coat of varnish has been applied, the abrasive material consisting of finely ground pumice stone mixed with water. The rubbing machine is placed upon the surface to be rubbed, and power being supplied, the rubbing pads are reciprocated.

The object of this invention is to provide means for preventing the water and pumice stone from being splashed or thrown into the mechanism or guideways of the machine in the reciprocation of the rubbing pads.

In the accompanying drawings, Figure 1 is a side elevation of a rubbing or polishing machine embodying the features of my invention. Fig. 2 is an under side view of the machine. Fig. 3 is a horizontal sectional view taken in the plane of dotted line 3-3 of Fig. 1. Fig. 4 is a fragmental vertical section taken in the plane of dotted line 4-4 of Fig. 3. Fig. 5 is a view similar to that of Fig. 4, but showing the parts in a different position. Fig. 6 is a fragmental end view. Fig. 7 is a view on dotted line 6-6 of Fig. 5.

The embodiment herein shown of the invention comprises a body 1 adapted to be supported upon the rubbing pads to be hereinafter described. Said body contains the mechanism for reciprocating the rubbing pads and supports an upper section which contains an electric motor 2 for driving said mechanism.

3 is a drive shaft. Upon the lower end of said shaft is fixed a pinion 4 that meshes with two spur gear wheels 5 suitably supported in the body 1. Each of the gear wheels 5 is connected by means of a crank pin 6 and a pitman 7 with slides 8. The slides 8 are mounted for movement toward and away from each other in a dove-tail guideway 9 formed in the lower side of the

body 1. The guideway 9 does not extend to the extreme ends of the body 1. The end walls of the guideway are indicated at 10.

The pad holders, to be later described, are detachably secured to the slides 8 by means of members 11, said members being affixed to the slides in any suitable way, as by means of screws 12. The members 11 are wider than the slides 8 so as to overlap the sides of the guideway 9. To prevent the entrance of water or pumice stone between the members 11 and the lower side of the body 1, I provide two parallel guard flanges 13 extending downwardly from the body 1 at opposite sides of the path of movement of the members 11.

In order that the guideway 9 shall be closed to the entrance of water or pumice stone from the space between the rubbing pads, each member 11 is provided with a guard extension 14 extending toward the other member 11, the guard extensions 14 overlapping in all positions of said members, as will be apparent from Figs. 4 and 5. The guard extensions 14 are of sufficient width to fill the space between the guard flanges 13.

In order to insure that water and abrasive material shall not enter the guideway 9 through the ends of the latter, each member 11 is provided with a guard extension 15 extending toward the adjacent end of the body 1, said extension being of such length as to extend outwardly beyond the end wall 10 when the members 11 are in their innermost position. The guard extensions 15 are of such width as to fill the space between the guard flanges 13.

16 are the pad holders. These holders may be secured to members 11 in any suitable way. Herein I have shown each holder as provided with a dove-tail guide 17 lying within a correspondingly shaped guideway 18 extending transversely of the members 11. Relative movement between the pad holder and its attaching member 11 may be prevented in any preferred way, as by means of set screws 19.

20 indicates a pad of any suitable material removably secured to each pad holder 16 and covering the lower side of the latter.

In operation, the rotation of the drive shaft 3 causes the pad holders 16 to reciprocate toward and away from each other, thereby rubbing the surface upon which the machine rests. The reciprocation of the pads 110

causes the mixture of water and pumice stone to be splashed, more or less, but the mixture cannot gain access to the guideway 9 or the mechanism located thereabove, since 5 the lower side of said guideway is closed by the guard extensions 14 and 15 in all positions of the pads.

I claim as my invention:

1. In a rubbing or polishing machine, a 10 structure having a guideway opening upon its lower side; two slides in said guideway; means for moving said slides; guards connected to said slides and extending below and closing said guideway against the entrance of liquid from below; and pads attached to the slides.

2. In a rubbing or polishing machine, a 20 structure having a guideway in its lower side; slides movable in said guideway; means for moving said slides toward and away from each other; a guard extension connected to each slide, said extensions extending toward each other and overlapping each other in all positions of said slides to 25 close the lower side of the guideway; and pads attached to the slides.

3. In a rubbing or polishing machine, a 30 structure having a guideway in its lower side; two slides movable in said guideway; means for moving said slides; a member fixed to each slide; a guard extension on each member, said guard extensions extending toward each other and overlapping each other in all positions of the slides; pad-holders 35 detachably connected to said members; and pads attached to the pad-holders.

4. In a rubbing or polishing machine, a 40 structure having a longitudinal guideway in its lower side, said guideway stopping short of the ends of the structure; two slides in said guideway; means for moving said slides; a guard extension connected to and extending outwardly from each slide and underlying said structure, said extensions 45 being of sufficient length to extend beyond the ends of the guideway when said slides are in their innermost position; and rubbing pads connected to said slides.

5. In a rubbing or polishing machine, a 50 structure having a guideway in its lower side, said guideway stopping short of the ends of the structure; two slides movable in said guideway; means for reciprocating said slides; a member fixed to each slide; a guard 55 extension on each member, said guard extensions extending toward each other and overlapping each other in all positions of the slides; a guard extension extending outwardly from each member and underlying 60 said structure, said last mentioned extensions being of sufficient length to extend be-

yond the ends of the guideway in all positions of the slides; a guard flange extending downwardly from the structure at each side of the path of movement of the members; pad-holders detachably connected to the members; and pads attached to the pad-holders.

6. In a surfacing machine, the combination of a structure having an open lower 70 side, a pair of surfacing elements mounted for reciprocation along said lower side, means for driving said elements, and horizontal guard extensions moving with said elements for closing the said open lower side 75 of the structure.

7. In a surfacing machine, a surfacing element having horizontal guard members projecting from opposite sides thereof and adapted to obstruct surfacing material 80 which splashes up.

8. In a surfacing machine, the combination of a structure having an open lower side, a pair of surfacing elements mounted on said structure to reciprocate toward and away from each other, means for driving said elements, guard extensions on the inner or adjacent sides of said elements projecting toward each other and arranged to overlap, and guards on the outer sides of said elements adapted to slidably coöperate with parts at opposite ends of said structure.

9. In a surfacing machine, the combination of a structure having an open lower side, a pair of surfacing elements mounted on said structure to reciprocate toward and away from each other, means positioned between said elements and extending from side to side of the structure and adapted to overlap and coöperate to maintain the mid-portion of the said open side closed at all times, and horizontal guard members on the outer sides of said elements arranged to coact with parts on opposite ends of said structure for the purpose described.

10. In a surfacing machine, the combination of a structure having an open lower side, a pair of surfacing elements by which the machine is supported upon the article to be finished, said elements being mounted adjacent to said lower side to reciprocate toward and away from each other, means for driving said elements, and overlapping horizontal guard devices between said elements for closing the open lower side of the machine.

In testimony whereof I affix my signature in presence of two witnesses.

PETER BAUKIN.
